FOUNTAIN PEN FOR CONCENTRATED INK

Eugen Wetzel, Haltingen, Baden, Germany

Application April 13, 1937, Serial No. 136,592
In Germany April 17, 1936

7 Claims. (Cl. 120—42)

The invention which will be hereinafter described relates to a fountain pen with a container for concentrated ink, coloring matter and the like, said container being movable relative to the holding body.

The fountain pens of all systems which are in commerce, are constructed in such a manner, that they must be filled with ink from time to time, the ink being sucked in by means of pistons or by vacuum. If by accident there is no ink at disposal, it is impossible to re-fill the fountain pen so that it cannot be used.

The object of the invention is to obviate this inconvenience.

Three embodiments of the invention are illustrated, by way of example, in the accompanying drawings in which

Fig. 1 shows in section a fountain pen according to the first form of construction.

Fig. 2 shows the fountain pen in elevation, the sleeve being removed.

Fig. 3 shows the fountain pen in sucking position.

Fig. 4 is a vertical section through Fig. 3.

Fig. 5 shows the fountain pen ready for writing.

Fig. 6 illustrates the filling process for the container for coloring matter.

Fig. 7 shows an ink cartridge, particularly constructed for filling the container for coloring matter.

Fig. 8 shows partly in vertical section a fountain pen of the second form of construction.

Fig. 9 is a similar view as Fig. 8 showing the piston in another position.

Fig. 10 illustrates how the filling of the upper container with coloring matter is effected.

Figs. 11 and 12 show the fountain pen according to the third form of construction in vertical sections in two different positions and

Fig. 13 in elevation.

The fountain pen according to the invention consists substantially, as shown in Fig. 1, of an ink container 1 and of a container 6 for the concentrated coloring matter and movable relative to the ink container. The ink container 1 is preferably made of transparent material and closed at the front end by a pen piece 2 carrying a pen 3 of glass, steel, gold or the like.

The rod 6 of a piston 5 serving as a sucking device forms a container for the concentrate. In this piston a discharge valve 7 and a closing cap 8 of rubber and the like are provided. The closing cap 8 is connected by control rod 9 or in any other suitable manner with a piston 10 mounted

in the container 6 and serving for the continuous emptying of the container 6 for the coloring matter or for pressing out the actually required quantity of coloring matter. A screwthreaded shaft 11 is rigidly connected with the piston 10 and carries a set nut 12, an abutment nut 13 and a counter-nut 14 constructed as a cap nut.

The fountain pen according to the invention is used as follows:—

The clamping or set nut 12 is screwed up to the abutment nut 13 (Fig. 2) whereupon the cap nut 14 is depressed until the container 6 for the coloring matter and with the same the piston 5 are pushed into the ink container 1 (Fig. 3). The air is thus pressed out of the ink container as in all known fountain pens of the piston systems.

At the same time the piston 10 in the container 6 for coloring matter moves inwards as can be seen from Fig. 4 and presses a certain quantity of coloring matter determined by the abutment nut 13 through the valve 7 which is opened.

The fountain pen is then dipped into water or into any other material and by means of the cap nut 14 the piston 5 is pulled up into the extreme position, so that the ink container 1 is filled with water which mixes with the coloring matter contained in the ink container 1, to form writing ink. Valve 7 has been automatically closed by the covering flap 8 during the suction stroke after, as equivalent for the discharged coloring matter, the corresponding quantity of air has been sucked into the container 6 for coloring matter, during the stroke of the piston. It is thereby prevented that in any position of the fountain pen more coloring matter can be dissolved and further the coloring matter dries as the container is now air-tightly closed. For security sake the set nut 12 is then screwed home as can be seen from Fig. 1.

A sleeve 4 (Figs. 1 to 4) serving as an abutment for the piston 5 has a screwthreaded extension 15 for a capsule 16 which has to be screwed on as shown in Fig. 5, to ensure a practical shape of the fountain pen.

As can be seen from the foregoing description, the operation of the fountain pen according to the invention differs from that of an ordinary fountain pen of the piston system only by the unscrewing of nut 12 prior to the pressing stroke and by screwing home of this nut after the sucking stroke.

The control of the valve or the mixing of the coloring matter or the dosing of the same are automatically effected. If the concentrate can be diluted 15 to 20 times, it is possible to employ

a quantity of concentrated coloring matter which lasts for 6 to 12 months. To re-fill the container 6 of coloring matter, a container 20 as shown in Fig. 6 is employed in that after unscrewing the cap nut 14 (Figs. 1-4) the container 6 for coloring matter is completely pulled out of the ink container 1 and pushed with its piston 5 into this container or cartridge 20. The nuts 12, 13 and 14 are then unscrewed from the screwthreaded shaft 11 and an extension piece 17 is screwed onto this shaft in any suitable manner.

In the position shown in Fig. 6 valve 7 is opened and during the suction stroke the container 6 is filled with coloring matter. In order that air 15 can flow into the cartridge 20 for coloring matter during the suction stroke the screw bolt 22 having an air channel 21 is slightly unscrewed.

After the above proceeding the extension piece 17 is removed, the nuts 12, 13 and 14 are screwed 20 onto the screwthreaded bolt 11 into the initial positions and the container for coloring matter is pushed into the ink container 1.

The cartridge of coloring matter is then airtightly closed by the nuts 22, 18 and 23, the packing 24 of cork or similar material preventing the coloring matter from flowing out.

The fountain pen constructed according to the invention may be filled with ink also in the usual manner, the fixing nut 12 being not loosened but 30 the pen being dipped into the ink after the pressure stroke, so that ink is sucked in, the valve 7 remaining permanently closed. It may be advisable to arrange the container for coloring matter in the protecting cap, so that this container 35 is under any circumstance separated from the ink container.

A fountain pen constructed according to the principle described may be carried out in a similar form as shown in Figs. 8 to 10. Two pistons 40 24 and 25 are mounted on a shaft 26, so that a double piston is formed. This double piston is adapted to move in a sleeve 1, which has one or several circular grooves 27. The moving downwards or upwards of the piston is effected by a 45 screw-threaded rod 31 with steep pitch, which is rigidly connected with a head 30 so that, when this head is turned the double piston is lowered or raised. Between head 30 and the corresponding end of sleeve 1 a short screwthreaded rod 29 is 50 inserted adapted to be screwed into an internal screwthread 32 and serving to connect the head 30 with the sleeve 1. Fig. 8 shows the double piston in the lowermost position. The concentrate is in the chamber formed between the two pistons 24 and 25, so that it is air-tightly shut off. The groove 27 is above the piston 24 so that it is 55 completely filled with concentrate. The fountain pen is then dipped into water or into any other similar liquid and the double piston raised by 60 turning head 30 so that water is sucked in (position shown in Fig. 9). The concentrate is moved upwards between the double pistons with the exception of the quantity filling the circular groove 27. This quantity mixes then with the water to 65 form writing ink.

Fig. 10 shows how the coloring matter is filled into the fountain pen. The intermediate piece 29 with the screwthreaded shaft is screwed out and the head 30 removed from sleeve 1. The double piston is then pulled out with the aid of the steep pitched screw 31 until the upper piston 25 is above the top end of sleeve 1. Concentrated coloring matter is then filled into sleeve 1 by means of a syringe or any other suitable instrument. The 70

double piston is then screwed down and the head 30 screwed on.

This form of construction presents in comparison with the first one the advantage that it is without valve, nozzles and the like so that not only the function is reliable but the manufacturing is extraordinarily simplified.

In the case 1 as shown in Figs. 11 and 12 a considerably larger chamber 33 for the concentrate is provided. Piston chambers 34 and 34a extend 10 from the lower and upper end of the enlarged chamber 33. The pistons movably mounted in the case consist each of an upper disc 36a and a lower disc 35, 35a of cork and of an intermediate disc 37, 37a of rubber or similar material. The 15 two pistons are fixed on a piston rod 26.

From the upper piston extends upwardly a screw spindle 38 with steep pitch. Into the upper intermediate screwthreaded end of case 1 the threaded end 39 of an end piece 40 is screwed 20 (Figs. 11 and 12) which in the inner end carries a packing 41. Through this packing a nut 42 with bore and internally threaded shaft extends, the upper end of said shaft being fixed in a knob 43 by a transverse screw 44. By turning knob 43 25 the piston is raised or lowered.

The space between the two pistons 35a and 36 is filled with coloring matter which moves together with the pistons and is not submitted to pressure. When the piston 35 is in the lowermost position, the extension piece 2 with the pen is dipped into a solvent, for instance water and the pistons are raised by corresponding turning of the knob 43, whereby the chamber 34 under piston 35 is filled with water M. In the inner 35 wall of chamber 34 an annular groove 37 is arranged which, when the piston is in the lowermost position, is filled with coloring matter, which when the piston is moved upwards again remains in this annular groove and is automatically mixed 40 with the water to form writing ink.

The fountain pen according to Figs. 11 to 13 possesses the special advantage, that by the rubber discs 37, 37a arranged between the cork discs 36a, 35a and 36, 35 respectively the enlarged 45 chamber 33 filled with concentrate K is airtightly closed and that by the packing 41 a good packing between this chamber and the turnable knob 43 is produced.

I claim:—

1. An improved fountain pen with a container for concentrated ink, coloring matter or the like, comprising in combination a tubular ink container, an extension piece screwed on the lower end of this container, a pen in this extension piece, a piston in the top of the said ink container, a discharge valve in said piston and a closing flap of rubber on said valve, a ring on the upper end of said ink container, an externally screw threaded extension at the top end of said ring, a container for concentrated coloring matter inserted in the extension of said ring, a piston in the upper end of said upper container, a rod downwardly extending from said piston and connected with said closing flap, a screw threaded rod upwardly extending from said piston in said upper container, a fixing nut screwed on this rod, a cap screwed on the top end of said screw bolt and an abutment nut under said cap.

2. Fountain pen as specified in claim 1, comprising in combination with the ink container grooves in the inner surface of the wall of said ink container designed to hold a necessary quantity of coloring matter for producing writing ink when mixed with water.

3. A fountain pen as specified in claim 1, comprising in combination a container comprising in its lower portion an ink container and in its upper portion a container for coloring matter, 5 said ink container having a circular groove in its inner wall and internal screw threads at the upper end, a piston rod in said ink container, a piston on the lower end, and a piston on the upper end of said piston rod, the lower piston 10 being underneath said groove when said rod is pushed down, a high pitch screw spindle in the top end of said upper piston, a short screw threaded rod adapted to be screwed into the upper end of said ink container, a head on the 15 top end of said screw threaded rod, and a nut between said head and the upper end of said container.
4. A fountain pen as specified in claim 1, comprising in combination with a case subdivided 20 into a lower chamber having an annular groove in its inner wall and an upper chamber, an intermediate chamber which is wider than said upper and under chambers, so that a large quantity of concentrated coloring matter can be stored in the 25 fountain pen.
5. Fountain pen as specified in claim 1, comprising in combination with the upper and lower compartments and a larger middle compartment, a vertical piston rod, a piston at the lower end, 30 and a piston at the upper end of said rod, said pistons consisting each of cork discs and of a rubber disc enclosed between said two cork discs 5 adapted to air-tightly close the space filled with coloring matter.
6. Fountain pen as specified in claim 1, comprising in combination with the upper and lower compartments and a larger middle compartment, a vertical piston rod, a piston at the lower end, 10 and a piston at the upper end of said rod, said pistons consisting each of cork discs and of a rubber disc enclosed between said two cork discs 10 adapted to air-tightly close the space filled with coloring matter and in the upper end of said case a head piece with internal packing of the upper end of said fountain pen.
7. A fountain pen as specified in claim 1, comprising in combination with the case, an upper and a lower chamber in said case, said lower chamber having an annular groove in its inner wall, and a larger chamber between these two chambers filled with coloring matter, a vertical 20 rod shiftable in said case, a piston on the upper end and a piston on the lower end of said rod, said upper piston ending at the top end of said larger middle chamber and said lower piston 25 engaging in the lower position in the lower chamber and in the lifted position clearing said annular groove filled with coloring matter and remaining at a certain distance from the lower end of said larger chamber to further enlarge the same. 25

EUGEN WETZEL.
